UNITED STATES PATENT OFFICE

145,231

DESIGN FOR A WALL SUPPORTED RADIO

Wilfred L. Schrader, Hartville, Ohio

Application October 17, 1945, Serial No. 122,904

Term of patent 7 years

(Cl. D56—4)

To all whom it may concern:

Be it known that I, Wilfred L. Schrader, a citizen of the United States, residing at Hartville, in the county of Stark and State of Ohio, have invented a new, original, and ornamental Design for a Wall Supported Radio, of which the following is a specification, reference being had to the accompanying drawing, forming a part thereof.

The single figure of the drawing is a perspective view of wall supported radio showing my new design. Both ends of the cabinet are the same in appearance.

I claim:

The ornamental design for a wall supported radio, as shown and described.

WILFRED L. SCHRADER.
